UNITED STATES PATENT OFFICE

ARTHUR SCHIFF, OF NEW YORK, N. Y.

SECTIONAL DISPLAY CABINET

Application filed March 26, 1929. Serial No. 349,979.

My present invention relates to sectional cabinets or the like for the convenient housing and display of maps, plans, charts and the like, and aims to devise articles of the general character specified which are simple in construction, which may be easily and conveniently fabricated and assembled, which are adapted in a convenient and very effective manner to house and display maps, plans, charts and the like, while having increased capacity for receiving and displaying such maps, plans, charts and the like, and while providing facilities for the ready removal of any of such maps, plans, charts and the like and their as ready return to the sectional cabinets from which they were removed. Other objects and advantages of the devices of the present invention will in part be pointed out in detail hereinafter and will in part be obvious to those skilled in the art to which the present invention relates.

In the accompanying specification I shall describe and in the annexed drawing show several illustrative embodiments of the devices of the present invention. It is, however, to be clearly understood that my invention is not limited to the specific embodiments thereof herein shown and described for purposes of illustration only.

Referring to the drawings in which I have shown the aforesaid illustrative embodiments of the present invention:

Fig. 1 is a perspective view of a plurality of sections in assembled relation;

Fig. 2 is a perspective view of a false top section;

Fig. 3 is a side view of a supporting pivot; and

Fig. 4 is a detail perspective view, on an enlarged scale, of one of the side walls of one of said sections and associated roller bracket and roller, all constituting one of the aforesaid illustrative embodiments of the present invention;

Fig. 5 is a front perspective view of a plurality of sections of different construction, constituting a portion of the second and remaining one of the aforesaid illustrative embodiments of the present invention;

Fig. 6 is a rear perspective view of the

sections assembled and illustrated in Fig. 5 of the drawing;

Fig. 7 is a front perspective view of the assembled device with one of the sections in open position so as to render it convenient to see the reverse side of the length of fabric attached to the spring-roller, thus doubling the capacity of the device since what is on the reverse side, no less than what is on the front side of the length of fabric attached to the roller is readily visible;

Fig. 8 is a perspective view of one of the intermediate sections; and

Fig. 9 is a perspective view of a bottom section, these different portions comprising the second and remaining one of the aforesaid illustrative embodiments of the present invention referred to above.

Referring now to the aforesaid illustrative embodiments of the present invention, and with particular reference to the drawings illustrating the same, and limiting the description for the time being to the form of the invention illustrated in Figs. 1 to 4, inclusive of the drawing, the sectional cabinet there illustrated and generally designated by reference character 20 comprises a plurality of main or intermediate sections 21 of which six are here shown by way of example merely. Each of the sections 21, as more clearly shown in Fig. 1 of the drawing, comprises a rear wall member 22, side wall members 23 and 24, and a front wall member 25, the sections 21 being of general open box-like configuration or construction. In their assembled form there is a space or gap 26 between the front wall members 25 of adjoining sections and also between the front wall member 25 of the lowermost section 21 and the bottom section 27. This is for the purpose of accommodating the brass or other metal or other binding strips 28 attached to the fabric lengths 29 which are in turn attached to the spring-rollers 30 and which carry the maps, charts, floor plans or the like 31 on their upper faces 29.

The side wall members 23 and 24 carry the usual brackets 32 for receiving and properly positioning the spring-rollers 30 in such a manner that any desired length of the fabric

55

60

65

70

75

80

85

90

95

100

length 29 may be pulled into display position against the action of the spring within the spring-roller 30 and held in such position by the usual pawl mechanism, such spring and 5 pawl mechanism not being deemed necessary to be shown here since it constitutes a part of a structure well known in the art.

Each binding strip 28 is provided with a manipulating knob 33. I also provide a brass 10 name plate 34 on each front wall member 25 to designate the nature of the map, chart, plan or the like housed within the particular section 21 to which the brass name plate 34 is applied.

15 I provide suitable means for conveniently and readily binding any desired number of sections 21 together and for as conveniently and readily disassembling the sections so associated to reduce or increase their number 20 as desired. While various means may be employed for this purpose, I prefer to employ the means illustrated comprising a plurality, here shown as three, adjustable securing rods 35, each preferably made up of interengaging 25 solid externally threaded male rod members 36 and hollow internally threaded female rod members 37 having the threaded portions 38 at the lower ends thereof. The threaded portions 38 are preferably of enlarged diameter 30 so that with a wrench or other suitable tool the two interengaging male and female rod portions 36 and 37 may be adjusted longitudinally with respect to each other to adjust the length of the rod members 35. While I have 35 shown three rod members at each side of the cabinet 20, it is apparent that I may use any other number, such as two or four, as desired.

In order to accommodate the securing 40 means 35, which preferably pass through the different sections 21, preferably through the lateral or side wall members 23 and 24 thereof, I provide such side wall members with 45 perforations or channels through which the rod members 35 may snugly or loosely pass so that the different sections 21 may be suitably assembled in the desired manner. I also prefer that the upper ends of the externally threaded male rod members 36 shall be 50 threaded to receive the wing nuts 39 for securing the rod members 35 in proper fixed relation with respect to the sections 21. It may here be stated that before applying the wing nut members 39, the male and female sections 55 36 and 37 respectively, making up the rod members 35 should be adjusted with respect to each other so that there will be only a small threaded upper portion of each male rod member 36 left for the wing nut members 39 60 to be screwed on to.

The bottom section 21 more clearly illustrated in Fig. 2 of the drawing is preferably provided with the series of threaded sockets 38' and 38'' at its sides 40 and 41 for receiving 65 the threaded lower ends 38 of the female rod

members 37. 42 indicates the rear portion and 43 the front portion of the bottom section 27 which may be hollow or solid as desired, depending on the construction utilized. 44 70 designates the top section more clearly shown in Fig. 1 of the drawing and being of general rectangular form and being provided on its under surface with the recesses 39' adjacent one side and 39'' adjacent the other side for receiving the wing nuts 39 and the upper threaded ends of the male rod members 36 75 secured by said wing nuts.

This completes the description of the construction of the embodiment of the invention 80 illustrated in Figs. 1 to 4, inclusive, of the drawing. The mode of assembling such embodiment will, it is believed, clearly appear 85 from the foregoing description but may be briefly summarized as follows: Assuming that the sections 21 are constructed as described above, and that the top and bottom sections 44 and 27 are constructed as described above, the lengths of the securing rods 35 are 90 adjusted to correspond to the number of sections 21 to be assembled, allowance being 95 made for the lengths at the upper and lower threaded portions of the rods which are to be received at the wing nuts 39, and at the threaded recesses 38' and 38'' of the lower section 27, the wing nuts 39 being removed, 100 the rods 35 are securely fastened in the threaded sockets 38' and 38''. The sections 21 are 105 then assembled over the rods 35, one on top of the other, each roller 30 and its length of fabric 29 bearing the map, charts, plan or the like 29', together with the associated binding strip 28 and operating knob 33 being inserted and properly positioned as its corresponding section 21 is applied in place. When all of the 110 sections 21 have thus been assembled, the wing nuts 39 are applied to the upper threaded ends of the rods 35 and the top section 44 placed on top of all.

In operation the device may be used somewhat as follows: Assuming that the rollers 115 30 are all in place with the maps, charts, plans or the like 29 applied to the respective upper faces 29', the user consults the brass name plates 34 and determines which map, plan, chart or the like he desires to consult. Having 120 determined this, he grasps the knob 33 attached to the binding strip 28 of the particular map, plan, chart or the like which he wishes to consult and pulls the same forward against the action of the spring in the spring-roller 30. The pawl mechanism already referred to and not deemed necessary here to be shown, will maintain the map, plan, chart or the like in extended display position as desired. The device may be restored to its initial position by further slightly drawing out the fabric 28 and then releasing it to be brought back into closed position under the action of the spring, not deemed necessary 125 130

here to be shown, in the particular spring-roller 30.

This completes the description of the construction, mode of assembly and operation of the form of the invention illustrated in Figs. 5, 1, 2, 3 and 4 of the drawing. It will be noted that the device is simple in construction, may be easily and economically fabricated, and conveniently and expeditiously assembled.

10 In operation the device will be found to be very compact and convenient and possessed of a wide range of utility. The device is very flexible, the sectional construction permitting any desired number of sections and thus of 15 contained maps, charts, plans or the like to be assembled together for convenient housing and display.

Referring now to the device illustrated in Figs. 5 to 9, inclusive, of the drawing, the cabinet there illustrated and generally designated by reference character 50, is also made up of a plurality of sections 51 here shown as being six in number, though any other desired number, greater or less than six, may be 20 conveniently employed. Each of the sections 51 is made up somewhat like the sections of the device previously illustrated. That is, each section 51 is of a general open box-like construction or configuration consisting of 25 the rear wall 52, the side walls 53 and 54 and the front wall 55. The side walls 53 and 54 are substantially rigidly associated with the rear wall 52. The front wall 55, on the other hand, is hingedly associated with one of the 30 side walls 53 or 54, such as the side wall 53. That is, at one of its ends the front wall member 55 is attached as by means of the inside hinge 56 to or adjacent to one end of the side wall members 53 or 54, here shown as the side 35 wall member 53. At its other end the front wall member 55 is preferably releasably attached as by means of a trigger spring catch mechanism 57 to the or adjacent the outer end of the remaining side wall member 54. This 40 construction is more clearly shown in Fig. 8 of the drawing.

While in the device already described the spring-roller and the brackets for supporting the same are carried by the side wall members, 50 in the form of the invention now being described such brackets and rollers are carried by the front wall members 55 which, as already indicated, is hingedly supported with respect to the remaining three wall members 55 of each section 51. This arrangement permits in the closed position of the front wall members 55 the top face of each length of fabric 58 to be exposed, while in the open position of the front wall member 55, as more 55 clearly shown in Fig. 7 of the drawing, the arrangement permits the ready exhibition of the reverse or lower side of the length of fabric 58 to either or both sides of which the maps, plans, charts or the like may be attached.

On the inside face of each of the wall members 55 is further carried a plurality of roller brackets 59 and 60 which in turn support the spring-roller 61 which is of the usual construction embodying a spring, not here deemed necessary to be shown, and also the usual pawl mechanism, also not here deemed necessary to be shown. One end of the length of the fabric 58 is attached to the spring-roller 61, while the other end is attached to the binding strip 62 which is provided with the manipulating knob 63 in the same manner as for the device already described. Also in the manner already described, there are spaces or gaps 64 between the front wall members 55 of successive sections 51 and also between the lowermost front wall member 55 and the bottom section 65 which is more clearly shown in Fig. 9 of the drawing and which is constructed in substantially the same manner as the lower section of the device already described.

In order to assemble the various sections 51 together with the bottom section 65 and the top section 66, which section is constructed substantially identical with the top section of the device already described, I use a series, here shown as two adjustable assembling bolts or equivalent members 67 which may be constructed identically with the adjustable sectional bolts made up of cooperating male and female rod members of the device already described. A pair of such assembling members 67 may be used at each side of the device, the same preferably passing through recesses or channels 53' and 54' in the side wall members 53 and 54 forming a part of each section 51. I prefer that the lower ends 67' of the assembling members 67 shall be threaded for cooperation with the threaded grooves 65' and 65'' for receiving such lower threaded ends 67' in the manner already described for the first form of the invention. Similarly, I prefer that the upper threaded ends 67'' of the assembling bolts or rods 67 shall be threaded to receive the wing nuts 68 for securing the different sections in proper relation with respect to each other and with respect to the assembling rods or other devices 67. 66' and 66'' designate recesses in the lower face of the top section 66 for receiving the wing nut 68 and the upper threaded portions 67'' of the rods or other assembling devices 67 as in the case of the device already described.

In order to assist in the assembling of the device and to render the registration of the different sections more accurate, I prefer to provide the lower face of each section at each of the side walls 53 and 54 with a bottom flange 53'' and 54'', there being corresponding grooves 51' and 51'' of each section 51 and corresponding grooves 66 and 66' in the upper face of the bottom section 65 for re-

ceiving the various flanges 53' and 54' when the device is assembled.

This completes the description of the second and remaining one of the aforesaid illustrative embodiments of the present invention. The manner of assembling such embodiment will, it is believed, be clear from the foregoing description and corresponds substantially in every detail to the manner of assembling the device already described and illustrated in Figs. 1 to 4, inclusive, of the drawing. The only point of difference in assembling this form of the invention is that in addition to having the assembling rods 67 pass through the grooves or channels 53' and 54' in the side members 53 and 54, respectively, of each section and having the lower threaded end 67' of each of the assembling rods 67 fit into the corresponding threaded socket 65' or 65'' of the lower section 65 and having the wing nuts pass over the upper threaded ends 67'' of the assembling rod 67 and rest in the recesses 66' and 66'' in the lower face of the top section 66, is that the bottom flanges 53'' and 54'' of each section 51 enter the grooves 51' and 51'' with the upper face of the section 51 immediately below and, in the case of the lowermost section, in the grooves 66 and 66', in the upper face of the bottom section 65.

The method of using the device illustrated in Figs. 5 to 9, inclusive, to the drawing will, it is believed, likewise clearly appear from the foregoing description but may be briefly described as follows: Assuming that the device is in the assembled position shown in Fig. 5 of the drawing, the operator consults any of the name plates 69 and having determined which of the maps, plans, charts or the like he desires to consult, he pulls on the knob 63 attached to the binding strip 62 and thus draws into display position the particular length of fabric 58 attached to this particular roller 61 on the upper face of which he will find the material he desires to consult.

The length of fabric 58 may be kept in exposed or display position against the action of the spring in the spring-roller 61 by the pawls forming a part of such spring-roller, neither the spring or the pawls being deemed necessary here to be shown. When he is through consulting the particular map, chart, plan or the like, he pulls the same a little further forward and then releases the same, whereupon under the action of the spring contained within the spring-roller 61 the length of fabric 58 is withdrawn to its original concealed position.

Assuming that the reverse or under face no less than upper face of the length of fabric 58 contains data, such as a map, chart, plan or the like which it is desired to consult, a trigger spring catch 57 of the particular section 51 containing the map, plan, chart or the

like desired to be consulted is released, the front wall member 55 carrying the spring-roller 61 is swung about its hinge 56 into the position shown in Fig. 7 of the drawing and the length of fabric 58 now pulled forward against the action of the spring, not here deemed necessary to be shown, in the spring-roller 61, and the map, plan, chart or the like on the reverse face of the supporting fabric 58 may now be consulted. It will thus be noted that in this way the capacity of the cabinet is doubled.

This completes the description of the construction, mode of assembly and mode of use of the device illustrated in Figs. 5 to 10, inclusive, of the drawing. It will be noted that such device is simple in construction, may be easily and conveniently fabricated and assembled, and is highly convenient in use. The device is very compact and permits the ready observation of data on either or both faces of the supporting fabric. The cabinet being sectional may be readily assembled in any desired number of units, the arrangement being such that the number of units may be increased or diminished for the proper adjustment of the securing means which are ideally constructed for this purpose.

Other superiorities and advantages of the devices of the present invention, particularly as exemplified in the aforesaid illustrative embodiments of the same, will readily occur to those skilled in the art to which the present invention relates.

What I claim as my invention is:

1. A section for a filing and display cabinet for maps, plans, charts and the like, comprising an open box-like member having a rear wall, side walls substantially rigidly associated with respect to said rear wall, a front wall hingedly secured adjacent one of its ends to one of said side walls and means for releasably securing the other of its ends to the remaining one of said side walls.

2. A section for a filing and display cabinet for maps, plans, charts and the like, comprising an open box-like member having a rear wall, side walls substantially rigidly associated with respect to said rear wall, a front wall hingedly secured adjacent one of its ends to one of said side walls and means comprising a trigger spring catch for releasably securing the other of its ends to the remaining one of said side walls.

3. A section for a filing and display cabinet for maps, plans, charts and the like, comprising an open box-like member having a rear wall, side walls substantially rigidly associated with respect to said rear wall, a front wall hingedly secured adjacent one of its ends to one of said side walls and means for releasably securing the other of its ends to the remaining one of said side walls, in combination with a spring-roller carried by said front wall and a length of fabric carried

by said spring-roller and adapted to carry a map, plan, chart or the like on either of its faces.

4. A section for a filing and display cabinet

5 for maps, plans, charts and the like, comprising an open box-like member having a rear wall, side walls substantially rigidly associated with respect to said rear wall, a front wall hingedly secured adjacent one of its ends to one of said side walls and means comprising a trigger spring catch for releasably securing the other of its ends to the remaining one of said side walls, in combination with a spring-roller carried by said front wall and a length of fabric carried by said spring-roller and adapted to carry a map, plan, chart or the like on either of its faces.

20 5. A section for a filing and display cabinet for maps, plans, charts and the like, comprising an open box-like member having a rear wall, side walls substantially rigidly associated with respect to said rear wall and a front wall hingedly secured to one of said side walls, in combination with a spring-roller carried by said front wall and a length of fabric carried by said spring-roller and adapted to carry a map, plan, chart or the like on either of its faces.

25 30 6. A sectional filing and display cabinet for maps, plans, charts and the like, comprising a plurality of sections of general open box-like configuration, each of said sections comprising a rear wall, side walls substantially rigidly associated with respect to said rear wall and a front wall hingedly secured to one of said side walls and adjustable means passing through said sections for securing together any desired predetermined number of said sections.

35 40 7. A sectional filing and display cabinet for maps, plans, charts and the like, comprising a plurality of sections of general open box-like configuration, each of said sections comprising a rear wall, side walls substantially rigidly associated with respect to said rear wall and a front wall hingedly secured to one of said side walls, in combination with a spring-roller carried by said front wall and a length of fabric carried by said spring-roller and adapted to carry a map, plan, chart or the like on either of its faces and adjustable means comprising a plurality of pairs of interengaging male and female rod members passing through said sections for securing together any desired predetermined number of said sections.

45 50 55 60 8. A sectional filing and display cabinet for maps, plans, charts and the like, comprising a plurality of sections of general open box-like configuration, each of said sections comprising a rear wall, side walls substantially rigidly associated with respect to said rear wall and a front wall hingedly secured to one of said side walls and adjust-

able means passing through the side walls of each of said sections for securing together any desired predetermined number of said sections.

9. A sectional filing and display cabinet 70 for maps, plans, charts and the like, comprising a plurality of sections of general open box-like configuration, each of said sections comprising a rear wall, side walls substantially rigidly associated with respect to said rear wall and a front wall hingedly secured to one of said side walls, in combination with a spring-roller carried by said front wall and a length of fabric carried by said spring-roller and adapted to carry a map, plan, 80 chart or the like on either of its faces and adjustable means comprising a plurality of pairs of interengaging male and female rod members passing through the side walls of each of said sections for securing together 85 any desired predetermined number of said sections.

10. A sectional filing and display cabinet 90 for maps, plans, charts and the like, comprising a plurality of sections of general open box-like configuration and adjustable means, the outer ends of which are threaded, passing through said sections for securing together any desired predetermined number of said sections, together with top and bottom sections, means for securing the threaded upper ends of said rod members, recesses in said top section for receiving said securing means, and threaded recesses in said bottom section for securely receiving the 100 threaded lower ends of said rod members.

11. A sectional filing and display cabinet 105 for maps, plans, charts and the like, comprising a plurality of sections of general open box-like configuration and adjustable means 110 comprising a plurality of pairs of interengaging male and female rod members, the outer ends of which are threaded, passing through said sections for securing together any desired predetermined number of said sections, together with top and bottom sections, means for securing the threaded upper ends of said rod members, recesses in said top section for receiving said securing means, and threaded recesses in said bottom section 115 for securely receiving the threaded lower ends of said rod members.

12. A sectional filing and display cabinet 120 for maps, plans, charts and the like, comprising a plurality of sections of general open box-like configuration, each of said sections comprising a rear wall, side walls substantially rigidly associated with respect to said rear wall and a front wall hingedly secured to one of said side walls and adjustable means, the outer ends of which are threaded, passing through said sections for securing together any desired predetermined number of said sections, together with top and bottom sections, means for securing the 125 130

- threaded upper ends of said rod members, recesses in said top section for receiving said securing means, and threaded recesses in said bottom section for securely receiving the threaded lower ends of said rod members.
13. A sectional filing and display cabinet for maps, plans, charts and the like, comprising a plurality of sections of general open box-like configuration, each of said sections comprising a rear wall, side walls substantially rigidly associated with respect to said rear wall and a front wall hingedly secured to one of said side walls, in combination with a spring-roller carried by said front wall and a length of fabric carried by said spring-roller and adapted to carry a map, plan, chart or the like on either of its faces and adjustable means comprising a plurality of pairs of interengaging male and female rod members, the outer ends of which are threaded, passing through said sections for securing together any desired predetermined number of said sections, together with top and bottom sections, means for securing the threaded upper ends of said rod members, recesses in said top section for receiving said securing means, and threaded recesses in said bottom section for securely receiving the threaded lower ends of said rod members.

In testimony whereof, I have signed my name to this specification this 13th day of March, 1929.

ARTHUR SCHIFF.
